ARTICLE OF FURNITURE

Hazel E. John and Eugene Allen John,
Seattle, Wash.

Application December 11, 1945, Serial No. 634,263

13 Claims. (Cl. 211—148)

1

The present invention is concerned with an article of furniture which may take various forms, the article being herein represented in the form of a table. More particularly it is intended as a table for the use of children, having incorporated in it convenient means for the storage of toys, books, play materials, and the like.

One of the objects of this invention is to provide a table of the nature indicated, which may readily be knocked down for shipment, and the parts of which when assembled will be securely and rigidly interlocked and braced in all its parts.

More particularly it is an object to provide such a knockdown article of furniture, in which the several parts are capable of interfitting by complementary notches, grooves, and the like, without the use of any tools, in such manner that each part holds previously assembled parts either positively locked in position, or frictionally so held, and each part as it is added further stiffens, braces, and strengthens the structure as a whole.

It is, too, a further object to provide such a knockdown table in which the various locking and stiffening elements serve the further purpose of affording supports or shelves for the support of books, toys, dolls, and the like, which are to be stored beneath the table, so that the greater part of the space beneath the table is thus usefully employed.

It is also an object to provide a knockdown article of furniture of the general nature indicated, which, in addition to being sturdy when assembled, is also of inexpensive and light construction.

With these and other objects in mind, as will appear hereafter, the invention comprises the novel parts, and the novel manner of assembling and relating these parts, as shown in the accompanying drawings, and as will be hereinafter more fully explained in this specification and defined by the claims which terminate the same.

In the accompanying drawings the invention is shown embodied in a knockdown table, and in a form which is at present preferred by us, but it will be understood that the invention may be incorporated in a different article of furniture, or for a different purpose, and it may also assume variant forms, within the scope of the invention as defined in the claims.

Figure 1 is an isometric exploded view of the parts, and Figure 2 is a similar view showing the parts assembled.

For the support of the table top 5 a substructure is formed, which substructure has the further function of affording storage space for the various articles for which a child has no ready place of

storage. This substructure generally consists of U-shaped end walls 1, of which there are two, somewhat spaced apart, two spaced side walls 2, disposed usually at right angles to the planes of the end walls 1, a lower horizontally disposed plate member 3, which is in the nature of a final locking member, as well as a large shelf, and smaller side shelf members 4, which also serve to make rigid and to hold properly spaced the upper portions of the end walls.

Each substantially U-shaped end wall 1 has a cross bar portion 10 and upright arm portions 11 at each side. The cross bar portions 10, in alignment with the inside edges of the upright arm portions, are vertically notched, as indicated at 12. The lower edges of the side walls 2 are complementally notched, as indicated at 22, so that these notches 12 and 22 can, in effect, interfit, and thereby the side walls 2 are held close against the inner edges of the upright arm portions 11, and the walls 1 and 2 mutually hold one another upright. Any equivalent interfitting arrangement to the same ends may be substituted for that described.

The shelf members 4 are to a degree optional, but highly desirable and useful. They are formed to interfit with the upright arms 11. When employed they must be assembled with the end walls 1 in advance of the engagement of the side walls 2 with the end walls, or else they must interfit therewith by means somewhat different from that about to be described. These shelf members 4 may interfit by reason of notches 43 in their outer edges, in which case the upright arm portions 11 of the end walls are complementally notched in their inner edges, as indicated at 13. Two such notches 13 in each arm portion 11 are shown. The lower of these is preferably in alignment with the upper edge of the cross bar portion, and the upper one is somewhat spaced thereabove. The shelf members 4 are of such width that when their notches 43 are interfitted with the notches 13 of the end walls, the inner edges of the shelves are flush with the inner edges of the upright arm portions 11. When thus interengaged with the end walls the shelf members serve to prevent the tilting of the end walls, and by employing two such shelf members at each side the rigidity of the structure is rather appreciable, even before assembly of the side walls 2.

When these side walls 2 are fitted into place, as previously described, they will lock in place the shelf members 4, for the latter are removable only by movement inwardly relative to the upright arm portions 11, and that is blocked by the

interposed side walls 2. The ends of the shelves, extending beyond the arm portions 11, serve as braces for the edges of the side walls 2, and are both useful and decorative.

When the side walls and end walls have been interfitted, the whole may be secured in assembled relationship by a plate member 3. It is not material precisely how this plate member 3 locks with the wall members, for it suffices if the plate member be merely of such width as to press the side walls 2 outwardly against the inner edges of the arms 11, but a convenient means of interlocking consists of providing grooves 23 in the inner surfaces of the side walls 2 at the level of the upper edge of the cross bar portions 10 of the end walls, forming the plate 3 of such width as to fit snugly within, and to span the space between, these grooves 23. When thus interlocked by movement of the plate member in its own plane, and with the plate member preferably of a length to extend beyond and rest upon at least one, and preferably upon each end wall, the end walls 1 and the side walls 2 are securely held in place.

The substructure so assembled, with or without the shelves 4, may constitute a useful article of furniture in itself, and may need no top; or, since the top performs the function of urging outwardly the upper portions of the side walls 2 against the inner edges of the upright arms 11, thereby assisting the plate 3 in frictionally holding the end walls 1 and side walls 2 against relative vertical separation, this function may be accomplished in part or wholly by an element which in all other respects is quite unlike the top 5. Any spacer element which thus urges apart the upper portions of the side walls 2 becomes the equivalent of the top, except as to the top's function of providing a working surface.

The shape of the top 5 is quite immaterial, and a round shape has been shown as one possible choice. It is removably secured upon the substructure, assembled as described below. Preferably the table top likewise interlocks to a degree with the substructure, as, for example, by providing on its under surface spaced cleats 50, far enough apart to fit closely between the upper portions of the side walls 2, and to urge the latter apart and to hold them close against the upper portions of the inner edges of the upright arm portions 11. Any convenient means of releasably securing the table top in this position, resting upon the upper edges of the walls, may be employed, such as the screw hooks 25 and the eyes 52. The top may be thus releasably secured to the end walls 1 or to the side walls 2; both types of wall preferably extend upwardly to contact the top.

As will be realized from comparison of Figures 1 and 2, this table is strong and rigid when assembled, yet the assembly can be quickly accomplished without the use of any tools. There is provided, by the plate member 3, a large ledge or shelf in the middle of the table for the support of large articles, such as dolls, small carts, and the like, or which with the top omitted might serve as a seat, flanked by the arms formed by the side walls 2. The shelf members 4 provide space for the reception of small trinkets, books, and the like, and the end portions of the shelf members 4 may be nicely rounded off, so that they are not only attractive in appearance, but avoid the formation of sharp corners on which a child may injure himself. The top 5, of course, provides a space on which to play and work. The plate member 3 is preferably located at a sufficient

height that the child cannot comfortably nor conveniently place his feet upon it, and so that it will serve primarily as a support for toys and the like. The whole table may quickly and easily be disassembled, without tools, and can be packed into extremely small compass for shipment.

All the parts of the table can be manufactured with a minimum of equipment, from such relatively inexpensive and light material as plywood. The only hardware is that involved in the top-securing means.

We claim as our invention:

1. An article of furniture comprising two spaced substantially U-shaped end walls having their arms disposed uprightly, and two spaced side walls abutting the inner edges of said upright arms of the end walls, said side walls and end walls being complementally notched to snugly interfit in such relationship by relative vertical movement, a substantially horizontal plate member of a length to extend past at least one end wall, and of such width that, when interposed between the two opposite side walls, at the level of the cross bars of the end walls, it urges the side walls against the inner edges of the upright arms of the end walls to deter relative vertical separation of the end and side walls, and locks such walls against wracking in a lateral sense.

2. An article of furniture comprising two spaced side walls and two spaced substantially U-shaped end walls having their arms disposed uprightly, the bottom edge of each side wall and the cross bar of each end wall, in alignment with the inner edges of its upright arms, being complementally notched to interfit in rectangular disposition, a substantially horizontal plate member of a width to span the distance between said side walls, and of a length to extend past each end wall, said side walls being grooved for the reception by lateral movement of the opposite edges of the plate, at the level of the upper edges of the cross bars of the end walls, to deter vertical separation of the side and end walls, and to lock such walls against deformation in a lateral sense.

3. An article of furniture comprising two spaced side walls and two spaced substantially U-shaped end walls having their arms upwardly directed, the bottom edge of each side wall and the cross bar of each end wall, in alignment with the inner edges of its upright arms, being complementally notched to interfit in rectangular disposition, the inner faces of the side walls being grooved at the level of the upper edges of the interfitted cross bars of the end walls, and a substantially horizontal plate member of a width equal to the distance between the bottoms of such opposite grooves, slidably received therein and urging the side walls outwardly against the upright arms of the end walls, to deter separation of the side and end walls.

4. An article of furniture comprising two spaced substantially U-shaped end walls having their arms directed upwardly, and two spaced side walls abutting the inner edges of said upright arms of the end walls, said side walls and end walls being complementally notched to snugly interfit in such relationship by relative vertical movement, a substantially horizontal plate member of a width to span the distance between said side walls, and of a length to extend past at least one end wall, at least one of the two opposite side walls being horizontally grooved to receive the edge of the plate member by such interengagement to brace the end and side walls against wracking in a lateral sense, and to deter

their relative vertical separation, and a top supported by the upper ends of certain of said walls, and maintaining the side walls outspread at their upper ends against the inner edges of the upright arms of the end walls.

5. An article of furniture comprising two spaced substantially U-shaped end walls each having its arms disposed uprightly, and two spaced side walls abutting the inner edges of said upright arms of the end walls, said side walls and end walls being complementally notched to snugly interfit in such relationship by relative vertical movement, a substantially horizontal plate member of a width to span the distance between said side walls, and of a length to extend past at least one end wall, at least one of two opposite side walls being horizontally grooved to receive the edge of the plate member, by such interengagement to brace the end and side walls against wracking in a lateral sense, and to deter their relative vertical separation, and a top supported upon and removably secured to the upper edge of the wall structure thus formed, and having spacer members closely fitting the inside portions of the uppermost and opposite wall members.

6. An article of furniture comprising two spaced side walls and two spaced substantially U-shaped end walls having their arms upwardly directed, the bottom edge of each side wall and the cross bar of each end wall, in alignment with the inner edges of its upright arms, being complementally notched to interfit in rectangular disposition, a substantially horizontal plate member of a length to extend past and rest upon the cross bar of the two end walls, and of a width to span the distance between said side walls, thus to hold the opposite side walls outwardly against the inner edges of the arms of the end walls, at the level of said upper edges of the cross bars of the end walls, to lock the side and end walls against deformation in a lateral sense, and to deter their separation in a vertical sense, and a top resting upon the upper edges of the walls, and secured to certain thereof by readily disengageable means.

7. An article of furniture comprising two spaced side walls and two spaced substantially U-shaped end walls each having its arms upwardly directed, the bottom edge of each side wall and the cross bar of each end wall, in alignment with the inner edges of its upright arms, being complementally notched to interfit in rectangular disposition, the inner faces of the side walls being grooved, at the level of the upper edge of the interfitted cross bars of the end walls, and a substantially horizontal plate member of a width equal to the distance between the bottoms of such opposite grooves, slidably received therein and urging the side walls outwardly against the lower portions of the inner edges of the arms of the end walls, a top resting upon the upper edges of the walls, cleats upon the under surface of the top spaced apart sufficiently to interfit between the upper edges of the opposite side walls and to urge the latter outwardly against the inner edges of the upper portions of the arms of the end walls, and readily disengageable means to secure said top to the supporting wall structure.

8. An article of furniture comprising two spaced substantially U-shaped end walls each having its arms extended upwardly, and two spaced side walls abutting the inner edges of said upright arms of the end walls, said side walls and end walls being complementally notched to interfit in

such relationship by relative vertical movement, a substantially horizontal plate member of a length to extend past at least one end wall, and of a width such that, when interposed between the two opposite side walls, at the level of the cross bars of the end walls, it urges the side walls against the inner edges of the upright arms of the end walls to deter relative vertical separation of the end and side walls, and to lock such walls against wracking in a lateral sense, and shelf members notched in the plane of the upright arm portions of the end walls, said upright arm portions being complementally notched to interfit therewith for support of said shelf members, and to space apart the upright arm portions thus joined.

9. An article of furniture comprising two spaced substantially U-shaped end walls each having its arms extended upwardly, and two spaced side walls abutting the inner edges of said upright arms of the end walls, said side walls and end walls being complementally notched to interfit in such relationship by relative vertical movement, a substantially horizontal plate member of a length to extend past at least one end wall, and of a width such that, when interposed between the two opposite side walls, at the level of the cross bars of the end walls, it urges the side walls against the inner edges of the upright arms of the end walls to deter relative vertical separation of the end and side walls, and to lock such walls against wracking in a lateral sense, and shelf members notched in their outer edges, adjacent each end, of a length to extend beyond the upright arm portions of the end walls at each side, said arm portions being complementally notched in their inner edges to interfit the shelf notches by relative lateral outward movement of the shelf members, and to leave the latter's inner edges substantially flush with the inner edges of the upright arm portions, for passage of the side walls.

10. A knockdown table comprising two spaced substantially U-shaped end walls, having their arms extended upwardly, and having vertical notches in the cross bar portion disposed in alignment with the inner edges of said upright arm portions, and having horizontal notches in such upright arm portions in alignment with the upper edge of the cross bar portion, and also spaced thereabove, shelf members each having complemental notched in its outer edge interfitting said horizontal notches in the arm portions of the end walls, to support the shelf members and to hold the upright arm portions rigid and spaced, said shelf members when so interfitted having their inner edges substantially flush with the inner edges of the upright arm portions, side walls notched at their lower edges to interfit the vertical notches in the cross bar portion of the end walls, and when so interfitted abutting the inner edges of the shelf members, to retain them in place, and of the upright arm portions, a substantially horizontal plate member, the inner surfaces of the side walls being grooved at the level of the upper edges of the cross bar portion of the end walls, and the plate member being of a width to be slidably received in said grooves, a top resting upon the upper edges of said walls, and readily releasable means to secure said top in such position.

11. An article of furniture comprising two substantially U-shaped end walls disposed side by side in upright planes, with their horizontal portions lowermost and their arms projecting up-

wardly, two side walls similarly spaced apart but disposed in upright planes which intersect the planes of the end walls, said side walls abutting the inner edges of the upright arms of the end walls, and notched to overlap the end walls at both sides of each thereof, and thereby to prevent relative approach or separation of the end walls, a substantially horizontal plate of a width and shape to extend between and to engage both side walls, in the vicinity of the horizontal portions of the end walls, and thereby to hold the lower portions of the side walls in contact with the inner edges of the arms of the end walls, and to prevent approach of such lower portions of the side walls.

12. An article of furniture comprising two substantially U-shaped end walls disposed side by side in upright planes, with their horizontal portions lowermost and their arms projecting upwardly, two side walls similarly spaced apart but disposed in upright planes which intersect the planes of the end walls, said side walls abutting the inner edges of the upright arms of the end walls, and notched to overlap the end walls at both sides of each thereof, and thereby to prevent relative approach or separation of the end walls, a substantially horizontal plate of a width and shape to extend between and to engage both side walls, in the vicinity of the horizontal portions of the end walls, and thereby to hold the lower portions of the side walls in contact with the inner edges of the arms of the end walls, and to prevent approach of such lower portions of the side walls, and means spacing apart the

upper portions of the side walls, similarly to hold the latter against the inner edges of the arms of the end walls, and to prevent approach of such upper portions of the side walls.

- 5 13. An article of furniture comprising two substantially U-shaped end walls disposed side by side in parallel planes with their arms projecting upwardly, two spaced side walls disposed at right angles to the end walls, and abutting the
10 respective inner edges of the upright arms of the end walls, and each having a depending lower portion which is interposed between and abuts the upright inner faces of the horizontal portions of the end walls, to maintain the latter spaced apart, a substantially horizontal plate member of a width and shape to engage the upright inner faces of and thus to space apart said side walls, and to rest upon the horizontal portions of the end walls, and means interconnecting and maintaining the spacing between the upper portions of the side walls.
